(57) **CLAIM**

The ornamental design for a tablet stand, as shown and described.

DESCRIPTION

FIG. 1 shows a top perspective view of a tablet stand according to an embodiment;

FIG. 2 shows a bottom perspective view thereof;

FIG. 3 shows a front elevation view thereof;

FIG. 4 shows a rear elevation view thereof;

FIG. 5 shows a left elevation view thereof;

FIG. 6 shows a right elevation view thereof;

FIG. 7 shows a top plan view thereof;

FIG. 8 shows a bottom plan view thereof;

FIG. 9 shows a front elevation view thereof with a tablet device mounted thereon; and,

FIG. 10 shows a rear elevation view thereof with a tablet device mounted thereon.

The broken line portion of the figure drawings is included to show unclaimed subject matter only and forms no part of the claimed design.

1 Claim, 10 Drawing Sheets
